(57) **CLAIM**

The ornamental design for a display screen of a medical device with icon, as shown and described.

DESCRIPTION

FIG. 1 is a front view of a first image in a sequence of a display screen of a medical device with icon according to a first embodiment of the claimed design;

FIG. 2 is a front view of a second image thereof;

FIG. 3 is a front view of a third image thereof;

FIG. 4 is a front view of a fourth image thereof;

FIG. 5 is a front view of a first image in a sequence of a display screen of a medical device with icon according to a second embodiment of the claimed design;

FIG. 6 is a front view of a second image thereof;

FIG. 7 is a front view of a third image thereof;

FIG. 8 is a front view of a fourth image thereof,

FIG. 9 is a front view of a first image in a sequence of a display screen of a medical device with icon according to a third embodiment of the claimed design;

FIG. 10 is a front view of a second image thereof;

FIG. 11 is a front view of a third image thereof;

FIG. 12 is a front view of a fourth image thereof,

FIG. 13 is a front view of a first image in a sequence of a display screen of a medical device with icon according to a fourth embodiment of the claimed design;

FIG. 14 is a front view of a second image thereof;

FIG. 15 is a front view of a third image thereof; and,

FIG. 16 is a front view of a fourth image thereof.

The subject matter in this patent includes a process or period in which an image changes into another image. This process or period forms no part of the claimed design.

(Continued)

The broken lines showing a display screen and portions of the icon form no part of the claimed design.
